RUG.

D. 16,759.

Patented June 29, 1886

UNITED STATES PATENT OFFICE.

RICHARD PAUL HEMMING, OF PHILADELPHIA, PENNSYLVANIA, ASSIGNOR
TO GEORGE W. ENNIS & CO., OF SAME PLACE.

DESIGN FOR A RUG.

SPECIFICATION forming part of Design No. 16,759, dated June 29, 1886.

Application filed May 27, 1886. Serial No. 203,476. Term of patent 3½ years.

To all whom it may concern:

Be it known that I, RICHARD PAUL HEMMING, a citizen of the United States, residing at Philadelphia, in the county of Philadelphia and State of Pennsylvania, have invented and produced a new and original Design for a Rug; and I do hereby declare that the photographic print accompanying this specification conveys to any one skilled in the art a clear understanding of the same, and is sufficient to enable such persons to use my invention.

The leading features of my design consist in a panel ornamented with conventional floral figures surrounded by an ornamental border. The center of the panel is ornamented by the representation of a dog's head set in a diamond shaped frame, the whole as shown in the photographic print.

What I claim as my invention is—

The design for a rug, consisting of a panel 20 ornamented with conventional floral figures surrounded by an ornamental border, and in the center a representation of a dog's head set in a diamond-shaped frame, all as shown in the photographic print.

R. PAUL HEMMING.
